DESIGN FOR AN EARRING OR SIMILAR ARTICLE

Michael Chernow, New York, N. Y.

Application May 29, 1946, Serial No. 130,208

Term of patent 7 years

(CL. D45—9)

To all whom it may concern:

Be it known that I, Michael Chernow, a citizen of the United States and residing at New York, in the county of New York and State of New York, have invented a new, original, and ornamental Design for Earring or Similar Article, of which the following is a specification, reference being had to the accompanying drawings, forming part thereof, and in which

Fig. 1 is a side view from the left of the earring showing my new design;

Fig. 2 is a front elevational view thereof; and

Fig. 3 is a side view thereof from the right of the earring.

I claim:

The ornamental design for an earring or similar article, substantially as shown.

MICHAEL CHERNOW.
